Patented May 28, 1918.

UNITED STATES PATENT OFFICE.

EGGE T. HILBRANDS, OF GREENE, IOWA.

MAIL RECEIVING AND DELIVERING APPARATUS.

1,267,664.

Specification of Letters Patent. Patented May 28, 1918.

Application filed October 20, 1917. Serial No. 197,669.

To all whom it may concern:

Be it known that I, EGGE T. HILBRANDS, a citizen of the United States, residing at Greene, in the county of Butler and State of Iowa, have invented certain new and useful Improvements in Mail Receiving and Delivering Apparatus, of which the following is a specification.

This invention relates to mail receiving and delivering apparatus, and more particularly to an improved device for use in connection with fast moving trains whereby mail may be received on the train or delivered therefrom without the necessity of diminishing the speed of the train and in a manner that will avoid the least possible danger to the person or persons operating the device.

One of the principal objects of the invention is to provide an auxiliary mail carrier mounted to travel at the side of the railway track whereby the carrier may travel with the mail car of the moving train when the latter is passing a mail transferring point for permitting the mail sacks to be removed from the carrier, taken into the mail car, or transferring mail from the mail car to the carrier.

A further object of the invention is to provide a carrier adapted to travel over a relatively long trestle at the side of the railway track, each end of the trestle being provided with means for automatically releasing the mail carrier when the train approaches the device for permitting the carrier to travel with the train for accomplishing the delivering and receiving of the mail sacks.

A further object of the invention is the provision of a device of this character that will be so constructed as to prevent any shock occurring when the mail car engages the carrier to travel with the latter for transferring the mail sacks.

A further object of this invention is the provision of a mail receiving and delivering apparatus which consists of comparatively few parts, and is simple in construction and durable and well adapted to withstand the rough usage to which devices of this character are ordinarily subjected.

For a full description of the invention and the advantages and merits thereof, reference is to be had to the following description and the accompanying drawings, where-

in is illustrated the preferred form of my invention, in which:—

Figure 1 is a side elevation, partly broken away and showing a portion of a mail car.

Fig. 2 is a horizontal section through a portion of a device. 60

Fig. 3 is a fragmentary end elevation.

Fig. 4 is a fragmentary plan, of the mail car and part of the mechanism associated therewith.

Fig. 5 is a fragmentary section on the line 65 5—5 of Fig. 4.

Referring to the drawing wherein is illustrated the preferred form of my invention, in which like numerals of reference indicate corresponding parts throughout the several views, the end standards 1 and 2 are laterally spaced apart and arranged near the side of the track. Longitudinally spaced, for a considerable distance from similar standards 1 and 2 are the standards 3. These pairs of standards should be spaced apart for a distance equal to the length of several blocks for a purpose which will presently appear. A trestle or runway 5 extends longitudinally between the pairs of standards and each end 80 of the runway is inclined to provide lifts 6' the height and angle of which may be made to suit the conditions. The runway consists of the rail 6 mounted upon ties 7 and the ends of the rails are fastened to the 85 standards and each lift 6' is reinforced by braces 8. The intermediate portion of the runway, as shown in Fig. 1 of the drawing, is disposed in a comparatively low plane so that the top of the rails 6 are level with the 90 top of the railway rails over which the train travels. In this manner grade crossings may cross the track and runway at any desired point since it may be necessary when the device is used with express trains to have 95 the runway 5 several hundred feet long.

Mounted upon the runway is a truck or carrier 9 which includes the platform supported by the standards 10 upon which the carrier wheels 11 are mounted. The truck 100 is adapted to travel on the runway 5 and the platform is provided with upright ends 12 the upper portions of which carry wheels 13 engageable with a retaining rail 14 disposed centrally above the runway and having inclined ends connected to the standard at the end of the runway. In this manner the carrier is assured of being held to

the runway when traveling from one end to the other thereof.

The inner edge of the platform has attached thereto a rack bar 15 the ends of which are curved upwardly and the bottom surface of the rack bar is provided with teeth. The mail car indicated at A is provided on its interior with bearing brackets 16 which support a shaft 17 the end of which projects through the side of the car near the door thereof, and carries a gear 18 in line with and engageable with the rack bar 15. The shaft 17, on the interior of the car, carries a pinion 19 in mesh with a gear 20 on a counter shaft 21 and this counter shaft has a heavy coil spring 22 mounted thereon, one end of which is fixed to the shaft while the outer end is fastened to one of the brackets 16. This construction is provided to absorb all shocks which would occur when the railroad car engaged the carrier.

Normally, the carrier is arranged at one of the inclined ends of the runway as indicated by dotted lines in Fig. 1, and is held in this position by a latch 23 pivotally mounted upon a cross rod 24 the ends of which are rotatably mounted on the standards 1 and 2. This latch is engageable with a latch dog 25 attached to the end of the truck for normally holding the end of the truck on the upper end of the lift 6' at one end of the runway. One end of the shaft or rod 24 carries a link 26, and this is connected with a flexible element 27 the end of which is joined to a lever 28 pivotally mounted on one of the railroad ties. This lever 28 is extended beneath the adjacent railway rail and, as shown to advantage in Fig. 3, its end is turned upwardly on the inner side of the rail, and a shoe 29 is carried by its end which will lie in the same plane as the top of the rail 2. A coil spring 30 holds the shoe in elevated position under normal conditions.

A cross arm 31 is extended laterally between each pair of standards and the terminals of the cross arms are fixed to the standards for supporting it in the desired position. Projecting from each cross arm is a pair of heavy coil expansion springs 32 the ends of which carry plates 33 and these plates are adapted to engage abutments on the end of the truck or carrier when the carrier is in position at either end of the runway. Under these conditions the springs will be compressed and it will be obvious that the moment the carrier is released the springs will impart a thrust to the truck for sending it forwardly on the runway.

The operation of the device is as follows:

The railway car A traveling in the direction indicated by the arrow in Fig. 1 approaches the device and the wheels of the locomotive will engage one of the shoes 29 and depress the same thus pressing down-

wardly on the member 28 and exerting a downward pull on the element 27 which in turn will pull the link 26 for turning the rod 24. Turning of this rod will lift the latch 23 which will disengage the latch dog 25 on the carrier and as soon as this releasing operation has been accomplished the heavy coil springs will be released and will thrust the carrier forwardly along the runway as indicated by full lines in Fig. 1. The mail car, still approaching the carrier by virtue of its greater speed, comes into position for permitting the gear 18 to engage the rack bar and the teeth of the gear meshing with the rack bar will cause the coil tension spring 22 to operate for absorbing any shock that would otherwise occur. In this manner the truck travels with the mail car for a considerable distance and at a point near the open door of the mail car whereby transfer of the mail may be accomplished. When the carrier reaches the end of the runway it will be immediately lifted by the lift 6' and raised to the position shown in dotted lines whereupon the latch 23 will automatically catch and the springs 32 will be compressed for retaining the carrier in position for the next operation in the opposite direction. If the truck is to transfer mail or receive mail from the next train traveling in the same direction as the first train, the latch 23 may be manually released and the springs will thrust the carrier along the runway to the opposite end where it may be held in position for the next operation.

The inclined ends of the trestle will serve to diminish the speed of the truck as it nears the ends of the trestle or runway so that it will approach the springs and the locking latches at the proper rate of speed whereby injury to the truck or the other mechanism will be prevented.

From the foregoing it will be observed that a very simple and durable mail receiving and delivering apparatus has been provided the details of which embody the preferred form. I desire it to be understood, however, that slight changes in the minor details of construction may be made without departing from the spirit of the invention or the scope of the claims hereunto appended.

I claim:

1. A mail bag transferring apparatus mounted at the side of a railway track, a carrier mounted at the side of the railway, a runway upon which the said carrier travels, standards arranged at each end of the runway and supporting the ends of the latter, the said standards carrying a pair of expansion springs engageable with the end of the said carrier, a latch mounted on each pair of standards and engageable with the truck to maintain the carrier in position against the action exerted by the said springs, a shoe arranged in close proximity

to one of the said rails, means connecting the shoe with the said latches to release the latter for permitting the springs to act upon the said truck, and a retaining rail disposed above the said truck for preventing displacement thereof from the said runway.

2. A mail bag transferring apparatus comprising a runway having inclined ends, the runway being arranged adjacent the side of a railway track, upright supporting standards at the end of the said runway, compression springs carried by the uprights at each end of the said runway, a carrier mounted on the runway and normally held on either one of the said inclined portions whereby either one or the other of the said springs may be compressed to exert a pressure on the end of the carrier arranged at either end of the runway, means for releasing the carrier from the compression springs, and means for maintaining the carrier on the runway when the springs impart a forward thrust to the same, the said carrier being provided with a rack bar, and means carried by the railway car to engage the said

rack bar for diminishing the shock of engaging the said carrier.

3. In combination with a railway car mounted on railway rails, shafting arranged within the car and carrying a gear disposed on the exterior of the car, a runway parallel with the said railway rails and including rails having their intermediate portions on the level with the said railway rails and their end portions inclined to form lifts at the ends of the runway, a carrier mounted on the said runway and including a platform level with the floor of the mail car when the said carrier is traveling over the intermediate portions of the runway, and a rack bar formed on the carrier and engageable with the said gear when the said carrier and mail car are moved into close proximity to each other.

In testimony whereof I affix my signature in presence of two witnesses.

EGGE T. HILBRANDS.
